CLAIM

The ornamental design for an archery release, as shown and described.

DESCRIPTION

A portion of the disclosure of this patent document contains or may contain material which is subject to copyright protection. The copyright owner has no objection to the photocopy reproduction by anyone of the patent document in exactly the form it appears in the Patent and Trademark Office patent file or records, but otherwise reserves all copyrights whatsoever.

FIG. 1 is a front elevation view of an embodiment of the archery release.

FIG. 2 is a rear elevation view of the embodiment of the archery release.

FIG. 3 is a right side elevation view of the embodiment of the archery release.

FIG. 4 is a left side elevation view of the embodiment of the archery release.

FIG. 5 is a top view of the embodiment of the archery release.

FIG. 6 is a bottom view of the embodiment of the archery release.

FIG. 7 is a front isometric view of the embodiment of the archery release; and,

FIG. 8 is a rear isometric view of the embodiment of the archery release.

The broken lines in the drawings are shown for illustrative purposes only and form no part of the claimed design.

1 Claim, 8 Drawing Sheets
